United States Patent Office.

CHARLES WILHELM AND JOSEPH NEUMANN, OF PHILADELPHIA,
PENNSYLVANIA.

Design No. 2,624, dated April 16, 1867.

DESIGN FOR A LANTERN REFLECTOR.

The Schedule referred to in these Letters Patent and making part of the same.

TO ALL WHOM IT MAY CONCERN:

Be it known that we, CHARLES WILHELM and JOSEPH NEUMANN, of the city of Philadelphia, in the State of Pennsylvania, have invented or produced a new and original Design for the Reflector and Case of an Out-Door, Stationary, Oblique Lantern; and we do hereby declare that the following is a full, clear, and exact description thereof, reference being had to the accompanying drawings, making a part of this specification, in which—

Figure 1 is a perspective view of the same applied; and

Figure 2 a vertical diametral section—

Like letters of reference indicating the same objects when in both figures.

These oblique lanterns are intended to be fixed near the outside upper ends of store windows for the purpose of throwing a strong light into the latter, the flame being protected from wind by a plain glass door fitting over the mouth of the case.

Referring to the drawings, A B is the case; C the glass door; D E the reflector; F a gas-burner; G a gas-supplying pipe, and H a glass chimney. The case A B has eight sides, converging by regular curves to a point at the centre of the back part of the same, each side being straight transversely, and presenting together a large octangular mouth in front. The latter is covered by the glass door C. The inner side of the case is painted white. The reflector D E consists of eight reflecting plates, cut and united together at their side edges, so as to present a reflector having eight sides of the same form as those of the case A B, but shorter and smaller, and secured within the former so as to leave an air space between them, as represented in the drawings. The inner side of the said reflector D E is polished silver. The burner F is in the focus of the reflector, and is supplied with gas by the pipe G, which passes through one side of the case and then upward to the burner. The glass chimney H passes vertically upward through appropriate holes in the upper sides of the reflector and case, as shown in the drawings.

What we claim as our invention, and desire to secure by Letters Patent, is—

The design for the reflector D E and case A B for an out-door, stationary, oblique lantern, as described and shown.
